UNITED STATES PATENT OFFICE.

SIDNEY M. STEVENS, OF DE KALB, ILLINOIS, ASSIGNOR, BY MESNE ASSIGNMENTS, TO WASHBURN & MOEN MANUFACTURING COMPANY, OF WORCESTER, MASSACHUSETTS, AND ISAAC L. ELLWOOD, OF DE KALB, ILL.

MACHINE FOR TWISTING BARBED FENCE-WIRE.

SPECIFICATION forming part of Letters Patent No. 272,095, dated February 13, 1883.

Application filed July 25, 1879.

To all whom it may concern:

Be it known that I, SIDNEY M. STEVENS, of De Kalb, in the county of De Kalb and State of Illinois, have invented certain Improvements 5 in Machines for Twisting Barbed Fence-Wire, of which the following is a specification, reference being had to the accompanying drawings, forming a part thereof.

In said drawings, Figures 1, 2, and 3 are respectively plan, side, and end views of a machine embodying my present invention. Fig. 4 is a central longitudinal vertical section. Fig. 5 is a cross-section through the bearing at the rear end. Figs. 6 and 7 are perspective 15 views of opposite sides of the spool-carrier.

As the invention has reference only to the mechanism for twisting the strand-wires between the barbs and for spooling the barbed and twisted wire, and not to the mechanism 20 for applying the barbs to the strand-wires, which may be of any ordinary or suitable construction, the former mechanism only is illustrated.

In the drawings, A represents the gear-wheel whereby the twisting-frame is operated. It is mounted upon the hollow journal b, supporting one end of the twisting-frame B B', which has also a hollow journal, b', at the other end. Both journals revolve in appropriate bearings, C. The frame upon the side B has a number of fluted or skeleton roller-guides, b², attached, which conduct the wire in the manner shown in Fig. 1 to the spool, the first one of these rollers being exactly at the mouth of the opening in the journal b, through which the wire is fed from the barbing mechanism. Skeleton or fluted rollers are used in order that the wire or fencing may be guided without interference from the barbs, 35 and they are arranged at intervals along a sinuous or undulatory line, so that the wire is carried along without being obliged to turn sharp corners.

B² is a cross-bar extending from side to side 45 of the frame, and holding rigidly the end of a right and left threaded screw D, whereon works back and forth the spool-carrier D'. This spool-carrier has at one side a sleeve, d, riding upon the exterior of the screw D, and

adapted for insertion through holes in the 50 heads of spool S, also lugs d' d', which hold the head of the spool S and rotate the same, also a sharp point or knife, d², which enters the wood of the head and holds the same when it has been inserted between the lugs, 55 such point being upon a shaft, d³, operated by a crank-handle, d⁴. The outer end of the sleeve d is squared interiorly, as at x, to receive and operate a square bar, E, passing through a sleeve, e, inserted in the journal b'. 60 This bar bears upon its end a round pin, e', which enters the end of the screw D, and thus forms a continuation of said screw. The center line of this rod and of the screw is also the center line of the twisting-frame, and it will 65 be seen that when the spool is placed upon the sleeve with its head secured to the carrier, as already described, it will rotate with the frame without throwing the same out of balance, and also that it will not disturb the balance of the latter when it does not revolve. The rod E, which revolves with the twister-frame and spool, is adapted to slide in the journal b', so that it may be withdrawn for the removal or replacement of the spool from 70 the holder without removing the latter from the twister-frame. During the twisting and spooling operations a pin, y, inserted through a hole in the rod, prevents its accidental displacement. In its travel back and forth one 75 end of the carrier D' slides on the rod E.

To secure the proper tension in winding the wire, a friction-brake consisting of shoes or clamping-pieces F F, held to their work by bands f f, which are strained by a weighted 80 lever, f', pivoted at f², is applied to a pulley, f³, upon the outer end of the sleeve e.

I have thus described all of the machine except the automatic devices for shifting the spool back and forth. These devices consist 90 of right and left nut-sections H H, held to the spool-carrier, and engaging the screw D alternately, together with devices for throwing them into and out of such engagement. The sections are inserted in a sliding head, h, having slots, wherein are placed pins h', to guide and hold it to the carrier. At either end of the head h is an elbow-lever, h², the part h³ of

which is an L-shaped spring, these levers being pivoted to the carrier and moving the head to and fro. Spring-latches h^4 are also secured to the carrier, and the projecting parts of the 5 spring-arms of the elbows extend over these latches, and they are intended to compress and release the latches alternately. In Fig. 6 one is shown as compressing one latch and the other as lying in the notch of the other latch, 10 leaving the latter comparatively free. The latches and spring-arms are changed from one position to the other by stops i and i' upon the frame, with which they come in contact, one latch and arm with one, and the other latch and 15 arm with the other, alternately. Thus when the spool has been carried to the end of the screw next to the bar B^2 the stop i strikes the inclined end of one of the latches and crowds it inward, so that the spring-arm of the elbow- 20 lever is left outside the notch in the latch. It then detains the spring-arm until the latter has passed down to the center of the latch, when the arm, by reason of its changed position, becomes free from contact with it. This 25 movement of the elbow-arm shifts the nut-bearing head from one side to the other, taking one nut-section out of engagement and putting the other into engagement with the screw, and reversing the movement of the spool. At the same time the other latch and spring-arm, 30 which, when the contact with the stop commenced, were in the same position in which such contact has just left the arm and latch directly acted upon by the stop, are put into the position first described—that is, with the arm within the notch of the latch—by the 35 operation of the elbow-levers and head, and the parts remain in this position until the spool has been carried to the other end of the screw, at which time the stop i' acts upon the last- 40 mentioned arm and latch in the same manner.

It is sometimes desirable to stop the spooling when the spool is intermediate between the ends of its reciprocating path and push it 45 back to the cross-bar B^2 , and it is always necessary that the spool should be close up to the cross-bar when the rod or shaft E is taken out preparatory to removing the spool. To permit this sliding of the spool and carrier upon the 50 screw it is only necessary to disengage both nut-sections H H , which can be done by putting the spring-arms in a position intermediate between the one shown in Fig. 6 and its reverse. It will be understood that the spool 55 and carrier are rotated by the wire which is being wound, and that if no wire is being wound the spool will not rotate, unless it be by friction.

In operation there will be instants of time 60 when the spool will be detained from turning with the frame by the brake, and at such times the detention will be in order that the spool may take up any slack which may exist in the wire. This, however, is scarcely preceptible 65 when the machine is operated at a reasonable speed, both frame and spool then seeming to move together. The brake also compensates

for the increase in diameter of the spool as it is filled.

In order that the wire may be fed along in 70 undulating lines and all sharp turns be avoided, I construct the frame with a twist, as shown in the drawings. This permits me to place the last roller around which the wire passes, and from which it is delivered directly 75 to the spool, in such a position, with its axis oblique to the radius of the spool, that it needs no change, as it delivers the wire equally as well to the empty as to the full spool.

The main feature of my invention can be 80 used in rendering off plain wire and twisting it preparatory to barbing by placing the spool or spools containing the same in the same line centrally and longitudinally in the frame, substantially in the manner indicated, the only 85 difference in such case being that the wire is fed away from instead of into this part of the machine.

I contemplate employing my invention with a twisting-frame supported wholly at one end; 90 but I believe that such use involves no departure from the principle of the invention.

The L parts of the arms h^3 look away from 95 each other, as shown in Figs. 6 and 7.

I identify the spool which is shown in the drawings by the letter S.

I claim—

1. The combination, with a twister-frame, spool, means for supporting the spool, and a 100 brake for regulating or controlling the tension exerted on the wire wound on the spool, of guides arranged, as set forth, to guide barbed fence-wire to the spool, substantially as described.

2. The combination of the rotary twister-frame having a hollow journal, the spool mounted in said frame with its axis coincident with the axis of the twister-frame, and the series of fluted or skeleton guide-rollers arranged in a sinuous or undulating line from 105 the mouth of said hollow journal to a point opposite the side of the spool, substantially as described.

3. The combination, with the twister-frame, spool-holder, and means for securing a spool 115 on said holder, of a rod journaled and supported, as explained, so as to revolve with the spool-holder, and adapted to slide in its bearing so as to allow the removal of the spool from its holder and the replacement of it 120 thereon without removing the holder from the twister-frame, substantially as described.

4. The combination of the twister-frame, the screw fixed thereto, the rod adapted to form a continuation of said screw or to be removed 125 by sliding in its bearing, and the spool-holder sliding on said rod and connected with said screw by a nut, substantially as described.

5. The spool-holder comprising, in combination with the main portion or body of the 130 holder, the sleeve, the lugs, the knife, the shaft of said knife, and the lever for operating it, substantially as described.

6. The combination, with the twister-frame,

spool-holder, and the stops on the twister-frame, of the divided nut and operating mechanism carried by the spool-holder for shifting said nut by engagement with said stops, substantially as described.

7. The combination, with the twister-frame and screw fixed thereto, of the spool-holder, the rod connected, as explained, with said spool-holder, so as to revolve with it, but adapted to allow the spool-holder to slide thereon, the brake applied to the said rod, and the connection between the spool-holder and the screw, substantially as described.

8. The combination, with a twister-frame, of a spool-holder provided with a sleeve for receiving the spool, and mounted in said frame with its axis coincident with that of the twist-

er-frame, and means, as set forth, for securing the spool on the holder, so as to permit it to be secured on and removed from the said holder without removing the latter from the twister-frame, substantially as described.

9. The combination of the frame B, provided with the hollow journals b b', and roller-guides b², with the screw D, sleeve d, carrier-body provided with lugs d' d'', knife or point d², shaft d³, handle d⁴, bar E, provided with pin e', sleeve e, clamp F F, bands ff, weighted lever f', and devices for connecting the said parts, substantially as specified.
